UNITED STATES PATENT OFFICE

2,323,107

OFFICE DESK

Bertha C. Wilson, Evansville, Ind.

Application May 17, 1941, Serial No. 393,905

1 Claim. (Cl. 45—70)

This invention relates to office desks and particularly to office desks provided with disappearing receptacles for holding office forms such as may be used by stenographers, clerks and executives.

The main object of the invention is to provide an office desk with a disappearing receptacle of the character described, which can be moved easily and quickly from a concealed position beneath the top or table of the desk to a conveniently accessible position on the desk.

Another object is to provide means for housing the receptacle beneath the desk top without interfering with the comfort of a person seated at the desk, and without impairing the appearance or normal efficiency of the desk.

The disappearing receptacle of my invention occupies the rear center portion of the desk table and employs space otherwise unused, thereby increasing the capacity of the desk in which it is embodied. When the receptacle is in raised, accessible position, ample room is left in front of it for all ordinary purposes. The receptacle can be reached with ease by a person seated in front of the desk, as well as by a stenographer using a typewriter supported by the conventional shelf provided at one side of the desk. When not in use, the receptacle may be moved downwardly out of sight, insuring safety and privacy of its contents.

Other objects and advantages will be apparent. In the drawings:

Fig. 1 is a front elevation of a desk embodying my invention, showing the receptacle in raised position on the desk, the dotted lines showing the position of the receptacle when concealed.

Fig. 2 is a plan view of the desk as it appears when the receptacle is concealed.

Fig. 3 is an end elevation, partly in section, the section being taken in the plane of the line 3—3 of Fig. 1.

Fig. 4 is a view similar to Fig. 3, but showing the receptacle in its lowered position.

Fig. 5 is a perspective view of the receptacle removed from the desk.

In that embodiment of the invention shown in the drawings, 10 indicates the desk as a whole, 11 the side drawer sections and 12 the legs. The upper rearward part of the space 13 between the drawer sections 12 accommodates the housing for the disappearing receptacle. The desk table 14 is cut away in its rearward center portion and provided with a lid 15 which has a countersunk ring pull 16. The receptacle housing comprises a front wall 17, bottom wall 18, 55

rear wall 19 and end or side walls 20, 20, provided with vertically disposed guide grooves 21.

The receptacle which is adapted to be housed in the aforementioned housing has rails 22 on its end walls 23 for sliding engagement with the grooves 21 of the housing walls 20. Said receptacle has a bottom wall 24, rear wall 25 and spacers 26, 26, one or more of which may be slotted as indicated at 27.

10 A pair of balancing devices 28, preferably of the conventional spring controlled, flexible tape type, are mounted under the table 14 at one side of each housing wall 20. One end of the tape 29 is connected at 30 to the bottom of the receptacle by a bracket 31.

The lid 15 is provided at each side near the rear edge with a pin 32 for pivotally mounting the lid in the table 14, the pivot pins 32 being slidable in grooves 33 in the walls 20. A stop 20 34 limits the movement of the lid 15.

The operation of the construction is as follows: To raise the receptacle from the concealed position in which it is shown in Fig. 4 and in dotted lines in Fig. 1, the user grasps the pull 25 16, lifts the lid 15, swinging it about the pivots 32 until the lid is vertically disposed, and then forces the lid downwardly until it occupies the position shown in Fig. 3. Then the user raises the receptacle by grasping one of the slotted 30 spacers 26, causing the rails 22 to slide upwardly in the grooves 21 of the housing walls 20 to the position shown in Figs. 1 and 3. The balancers 28 aid in the raising of the receptacle.

To lower and conceal the receptacle, the user 35 pushes downwardly on the receptacle, forcing it into its housing until the lower ends of the rails 22 contact the bottom wall 18 as shown in Fig. 4, and then moves the lid 15 vertically upwardly until the pins 32 are at the top of the grooves 33, 40 whereupon the lid can be moved pivotally to closed position flush with the table 14.

The receptacle may be varied in size and shape and may be designed to hold a great variety of forms and papers.

45 Changes may be made in details of construction without departing from the scope of my invention.

I claim:

A desk provided with a disappearing receptacle, comprising a table having a rectangular opening therein, a receptacle housing communicating with said opening and comprising side and end walls depending from the margins of said opening and a bottom horizontal wall, a pair of parallel vertical guide grooves disposed on each

end wall and extending to said bottom wall, a receptacle having a horizontal bottom wall and vertical end walls, a pair of guide rails disposed on each of said last end walls in sliding engagement with said guide grooves, with said rails extending below said last bottom wall for engagement with said first bottom wall to limit downward movement of said receptacle in said housing, a balancing device supported by said table adjacent each end wall of said housing and operatively connected with said receptacle for

5 maintaining same in raised position, other guide grooves in the rear end portions of said first end walls rearwardly of said receptacle and parallel with the first mentioned guide grooves, and a lid having pivot pins engageable in said other guide grooves for vertical sliding movement of said lid in uncovering said opening and for pivotal movement thereof to a horizontal position in covering said opening.
